UNITED STATES PATENT OFFICE

153,501

DESIGN FOR A DOUBLE BOILER

Dave Chapman, Chicago, Ill., assignor to Club Aluminum Products Co., Chicago, Ill., a corporation of Delaware

Application June 10, 1946, Serial No. 130,589

Term of patent 14 years

(Cl. D44—1)

To all whom it may concern:

Be it known that I, Dave Chapman, a citizen of the United States and a resident of Chicago, county of Cook, and State of Illinois, have invented a new, original, and ornamental Design for a Double Boiler, of which the following is a specification, reference being had to the accompanying drawing, forming a part thereof, in which Fig. 1 is a view in side elevation of a double boiler showing my new design; Fig. 2 is a top plan view of the same on a reduced scale; Fig. 3 is a vertical sectional view through the lower vessel of the boiler; and Fig. 4 is a vertical sectional view through the upper vessel and cover thereof of the boiler on substantially the scale of Fig. 1.

The characteristic features of the design reside in the handle and cover portions thereof.

I claim:

The ornamental design for a double boiler, substantially as shown and described.

DAVE CHAPMAN.
